[57] CLAIM

The ornamental design for a purse, as shown and described.

DESCRIPTION

FIG. 1 is a perspective view of a purse showing my new design;

FIG. 2 is a bottom rear perspective view thereof, an intermediate portion of the carrying strap broken away and omitted for convenience of illustration;

FIG. 3 is a front perspective view with the flap in an open condition, an intermediate portion of the carrying strap broken away and omitted for convenience of illustration; and

FIG. 4 is a bottom plan thereof with the flap partially raised.
